THERMOELECTRIC APPARATUS FOR HEATING OR COOLING OF FLUIDS

Matthew G. Ryan, Dewitt, and Addison C. Scheckler, Cato, N.Y., assignors to Carrier Corporation, Syracuse, N.Y., a corporation of Delaware

Filed Apr. 9, 1959, Ser. No. 805,285

3 Claims. (Cl. 62—3)

This invention relates to thermoelectric apparatus and more particularly to thermoelectric apparatus for heating or cooling of fluids, such as hot water heaters.

Hot water heaters of the prior art conventionally employ electrical resistance or combustible fuel fired heating elements. Where electrical resistance heaters are employed the amount of available heat produced for heating water in a hot water tank is limited by the heat dissipated in the resistance elements and the coefficient of performance cannot exceed unity. In a fuel fired burner a substantial portion of the heat produced by combustion of the fuel escapes through the exhaust stack and is unavailable for heating the water. Thermoelectric elements, on the other hand, may be connected so as to produce heat at their hot junctions in excess of the energy supplied by the electrical power source by reason of the heat absorbed from ambient fluids at the cold junctions. Furthermore, thermoelectric elements possess the advantage of being adapted to produce either heating or cooling at a particular location by merely reversing the flow of current through the elements so that a hot water heater may be designed which will serve as a source of chilled water by merely reversing the flow of current through the heater.

It is a principal object of this invention to provide an apparatus which utilizes the superior properties of thermoelectric elements for the tempering of fluids.

It is a further object of this invention to provide a thermoelectric apparatus adapted to heat fluids such as water while at the same time cooling surrounding fluids such as air.

These and other features of this invention which will become apparent by reference to the following description and appended drawings, are achieved by arraying a plurality of thermoelectric elements axially lengthwise on the outside of a tank in a manner to provide either hot or cold junctions adjacent the tank and in heat exchange relation with the fluid in the tank. The other thermoelectric junctions are remote from the tank and in heat exchange relation with a second fluid such as ambient air by means of a pin fin heat exchanger.

In the drawings:

FIGURE 1 is a cross sectional view of a thermoelectric fluid tempering apparatus constructed according to the instant invention; and

FIGURE 2 is a cross sectional view taken substantially on line II—II of FIGURE 1.

Referring particularly to FIGURE 1 a thermoelectric fluid tempering apparatus, such as a hot water heater, is designated generally at 10 and comprises a thermoelectric heat exchange assembly 11 in conjunction with a tank 12. Tank 12, is shown in the drawings as having a layer of insulation 13 which surrounds the walls of the tank and which, as also shown in the drawing, may surround the thermoelectric heat exchange assembly. The tank 12 has an inside wall 31 and an outside wall 32 with fluid inlet port 14 and fluid outlet port 15. The tank employed may be of any desired type having one or more shells and may be lined with glass, porcelain or enamel.

Tank 12 may also be provided with one or more internal apertured baffles 16 having apertures 17 therein ar-

2

ranged transversely along the axis of the tank. Where a plurality of baffles 16 are employed within the tank the apertures 17 may be staggered with respect to one another as shown in the drawing to provide circulation of the fluid within the tank when fluid is withdrawn therefrom. The baffles 16 serve to divide the fluid containing compartment of tank 12 into a number of smaller compartments, the purpose of which will be more fully explained.

Thermoelectric heat exchange assembly 11 is shown in the drawing to comprise a plurality of thermoelectric elements 19 disposed between a plurality of jumpers 20 and 21 which in turn are sandwiched between sheets of electrical insulation 22 and 23, which may comprise a mica filled epoxy resin film. As will be understood by those skilled in the art, thermoelectric elements 19 are of alternating P-type elements and N-type elements connected in series by jumpers 20 and 21 so that each jumper contacts one N-type element and one P-type element forming either hot or cold junctions at each jumper depending upon the direction of current flow through the thermoelectric elements. Groups of series connected thermoelectric may be connected in parallel for efficient operation if desired depending upon the voltage of the power source.

In the drawing all of the thermoelectric elements 19 are shown disposed outwardly away from axis of the tank and arrayed in an area extending axially lengthwise of the tank. The thermoelectric elements are also shown in the drawing to be connected in a row of three series connected thermoelectric elements which row is connected in series with the row next below it and so on throughout the length of the thermoelectric heat exchange assembly. Electrical conductors 36 and 37 are connected to the thermoelectric elements at the ends of each series group for connection to an appropriate source of electric current.

Jumpers 20, which connect one N-type thermoelectric element to one P-type thermoelectric element in that order for a given direction of current flow, are disposed adjacent outside wall 32 of tank 12 and jumpers 21, which connect one P-type element to one N-type element for the same direction of current flow, are disposed outwardly and remote from tank wall 32 with reference to the axis of the tank. It will be understood that when current flows in one direction through the thermoelectric elements that the one kind of junctions formed between the thermoelectric elements and jumpers 20 will be hot and that the other kind of junctions formed by jumpers 21 with the thermoelectric elements will be cold. If the direction of the current through the thermoelectric elements is reversed the junctions formed by jumpers 20 will be cold and those formed by jumpers 21 will be hot.

Heat exchanger 28, which may comprise a vertically disposed air chimney, is associated with the junctions formed by jumpers 21. The air chimney heat exchange means may comprise a pair of spaced parallel supporting plates 25 and 26 between which are disposed a plurality of small pin fins 24 of circular or other appropriate cross-section having a substantial area of surface contact with a second fluid such as air which is adapted to pass through the chimney 28. Sides 27 of supporting plate 26 may be bent at right angles to plate 26 and thereby form the sides of the chimney. If the chimney is surrounded by insulation 13 as shown in the drawing appropriate apertures 33 and 34 are provided in insulation 13 to permit the passage of the second fluid. A pin fin is characterized in that it generally has a length greater than its circumference. It will be understood that fluids other than air may be passed through the chimney and that appro-

priate heat exchange means will be employed for whatever fluid is used. Likewise other types of heat exchangers may be employed to transfer heat at the junctions formed by jumpers 21.

Electrical insulation sheet 23 separates supporting plate 25 from jumpers 21 but like insulation sheet 22 is made sufficiently thin so as not to unduly obstruct passage of heat between the first fluid in the tank and the second fluid passing through the heat exchange means. If additional heat exchange surface within the tank is required it may be achieved by extending a plurality of pins 29 from internal wall 31 of the tank, adjacent the area in which the thermoelectric elements are positioned, inwardly toward the tank axis.

When the thermoelectric fluid tempering apparatus of this invention is employed as a hot water heater, current is passed through the semiconductor materials which comprise the thermoelectric elements in a direction such that jumpers 20 adjacent a wall of the tank 12 form the hot junctions and the cold junctions are formed by jumpers 21 remote from the wall of the tank. Since the first fluid, such as water in this case, contained within the tank is in heat exchange relation with the hot junctions by reason of its close proximity to them it will be warmed. The second fluid, such as air, which is in heat exchange relation with the cold junctions will give up a portion of its heat to the cold junctions and the energy of this heat will be electrically pumped through the thermoelectric elements and be given up to the water in the tank. After the air is thereby cooled it will tend to flow downwardly in vertical chimney 28 because of its greater density and be discharged through aperture 34 in insulation 13 at the bottom of the tank. Warm air will, of course, enter aperture 33 at the top of the tank and circulate downwardly as it is cooled.

If the cold junctions of the thermoelectric elements are operated at a temperature below the dew point of the air entering aperture 33, water will be condensed from the air and the air discharged through aperture 34 will consequently be dehumidified. An appropriate receptacle (not shown) may be provided for the condensate. If the hot water heater is operated in the basement of a home or other building it will be seen that the thermoelectric fluid tempering apparatus of this invention provides a convenient means of dehumidifying the air therein while at the same time functioning as a hot water heater.

Thermoelectric elements characteristically operate with greater heat pumping efficiency if the temperature differential across them is small. It will be seen that, in a tank comprising a single chamber, warm water will normally circulate freely by convection and maintain a substantially equalized water temperature throughout the tank. The thermoelectric elements at the bottom of the tank, where cold air is in heat exchange relation with jumpers 21, may be subjected to a greater temperature differential between their junctions than those of the thermoelectric elements near the top of the tank at a location where air which has entered through aperture 33 has not been substantially cooled below ambient temperature.

In order to maintain a more even temperature differential between the junctions of the thermoelectric elements internal baffle plates 16 with staggered apertures 17 therein, as previously described, may be provided. Cold water entering inlet port 14 is thereby prevented from unrestrictedly circulating throughout the entire tank. It will be seen that the coldest water in the tank is contained in that chamber adjacent the thermoelectric elements which are in heat exchange relation with the coldest air in the air chimney and the warmest water is adjacent those thermoelectric elements which are in heat exchange relation with the warmest air in the chimney. A more uniform temperature differential is consequently achieved across the junctions of all of the thermoelectric

elements and the coefficient of performance of the apparatus thereby improved.

It will be understood that by reversing the current flow through the thermoelectric elements that the junctions adjacent the tank wall will become cold and that under such circumstances the thermoelectric apparatus may be employed as a water chiller.

While there has been described and shown a preferred form of this invention it will be understood that the invention may be otherwise embodied within the scope of the following claims.

We claim:

1. A combination thermoelectric hot water heater and ambient air dehumidifier comprising a hollow tank having a vertical axis and being adapted to contain water to be heated, inlet means adjacent the lower end of said tank and outlet means adjacent the upper end of said tank, a thermoelectric assembly comprising a plurality of dissimilar thermoelectric elements electrically connected to provide a plurality of hot junctions and a plurality of cold junctions upon the passage therethrough of an electric current in a predetermined direction, means to pass an electric current in a predetermined direction through said thermoelectric elements, said plurality of hot junctions being located adjacent and in heat exchange relation with a side wall of said tank, said plurality of cold junctions being radially spaced from said plurality of hot junctions with respect to the said vertical axis of said tank, means forming an air chimney for the passage of ambient air in heat exchange relation with said cold junctions, extended heat transfer means adapted to transfer heat from ambient air to said cold thermoelectric junctions, said extended heat transfer means being disposed vertically within said air chimney to induce a downward flow of air thereacross in order to cool the ambient air below its dew point to dehumidify said air while heating the water within said tank and means to prevent condensate formed by cooling of said ambient air from electrically short circuiting said cold junctions including relatively thin electrical insulation means separating said cold junctions from said condensate.

2. In a thermoelectric hot water heater and ambient air dehumidifier, a hollow vertical tank having an axis and adapted to contain water to be heated, inlet means adjacent a lower axial end of said tank and outlet means adjacent an upper axial end of said tank, a thermoelectric assembly located adjacent an exterior wall of said tank and insulated therefrom by a sheet of insulation, said thermoelectric assembly comprising a plurality of thermoelectric elements electrically connected by a plurality of jumpers of electrically conducting material to form thermoelectric junctions of a type adapted to be heated and thermoelectric junctions of a type adapted to be cooled upon the passage therethrough of an electric current in a predetermined direction, means to pass an electric current through said thermoelectric elements in a predetermined direction, said junctions of the type to be heated being located adjacent and in heat exchange relation with said wall of said tank, said junctions of the type to be cooled being located remote from said wall of said tank and being aligned substantially parallel to the axis of said tank to cool and induce a downward movement of ambient air about said thermoelectric assembly, said junctions of the type to be cooled being spaced from said axis of said tank a greater distance than said junctions of the type to be heated, partition means in the interior of said tank to prevent free convection of water within said tank thereby to promote heat exchange between thermoelectric junctions adjacent the lower end of said tank and the relatively cool water admitted through said inlet adjacent the lower portion of said tank, said last named means also serving to promote heat exchange between thermoelectric junctions adjacent the upper portion of said tank and the relatively warmer water in the upper portion of said tank

so as to maintain a relatively uniform temperature difference across the thermoelectric elements of said thermoelectric assembly, and heat transfer means including an extended heat transfer surface associated with said thermoelectric junctions of said type to be cooled to promote heat exchange between said last named junctions and ambient air to progressively cool the air induced downwardly below its dew point thereby condensing moisture from said air and dehumidifying it while maintaining substantially the same temperature differential across each of said thermoelectric elements to improve their performance.

3. A thermoelectric fluid tempering apparatus comprising a hollow tank having an axis and adapted to contain a fluid to be tempered, inlet means adjacent one axial end of said tank and outlet means adjacent the opposite axial end thereof, a plurality of substantially axially transverse perforated baffle means spaced along the axis of said tank, said baffle means dividing said tank into a plurality of axially aligned interior compartments having restricted communication therebetween, a thermoelectric assembly comprising a plurality of thermoelectric elements, said thermoelectric assembly extending axially along a wall of said tank, said thermoelectric elements having dissimilar thermoelectric properties and being electrically connected to form thermoelectric junctions of a type adapted to be heated and thermoelectric junctions of a type adapted to be cooled upon the passage therethrough of an electric current in a predetermined direction, junctions of one of said types being further remote from the said axis of said tank than the junctions of the other of said types to minimize direct heat

5 transfer from the heated junctions to the cooled junctions, thermoelectric junctions of one of said types being located in heat exchange relation with said plurality of said interior compartments of said tank and the thermoelectric junctions of the other of said types being adapted 10 for heat exchange with an ambient fluid exterior of said tank, means to pass an electric current through said thermoelectric elements in a predetermined direction, means to promote passage of said ambient fluid in heat exchange with said other thermoelectric junctions in a direction opposite to the flow of fluid through said tank from said inlet means to said outlet means so that a relatively uniform temperature differential may be maintained across the junctions of said thermoelectric elements thereby improving the performance of said thermoelectric fluid 15 tempering apparatus.
